UNITED STATES PATENT OFFICE.

BERTINI T. WOOD, OF BERLIN, WISCONSIN.

HOOP FOR MILK-CANS.

SPECIFICATION forming part of Letters Patent No. 716,800, dated December 23, 1902.

Application filed January 21, 1902. Serial No. 90,709. (No model.)

To all whom it may concern:

Be it known that I, BERTINI T. WOOD, a citizen of the United States, residing at Berlin, in the county of Green Lake and State of Wisconsin, have invented a new and useful Hoop for Milk-Cans, of which the following is a specification.

This invention relates to cans such as are used for holding and shipping milk and similar products; and it has for its object to provide as an article of manufacture a bottom or base hoop for such cans which will be cheap of manufacture and which may be easily applied and will be most effective in protecting the bottom of the can during the rough treatment to which it is subjected.

A further object of the invention is to provide a hoop made from a single strip of sheet metal and wherein the elements will be so disposed with relation to each other that they will not be displaced under the strains to which they are subjected.

In the drawings forming a portion of this specification, and in which like numerals of reference indicate similar parts in both views, Figure 1 is a perspective view showing the complete hoop constructed in accordance with the present invention. Fig. 2 is a vertical central section taken through the hoop and the lower portion of the can engaged therewith.

Referring now to the drawings, the hoop consists of a strip 5, of sheet metal, having an outwardly-directed bead 6 at one edge thereof, this strip having its ends connected, as shown. The metal of the lower portion of the hoop remote from the bead is bent inwardly and upwardly to lie against the inner face of the hoop, as shown at 7, and the upper portion of this inwardly and upwardly bent part 7 is bent in the direction of the center of the hoop and at right angles to form a shelf 8.

In the formation of the hoop a strip of metal of suitable width is cut to a length proper to make the hoop of the desired diameter, and either previous to the cutting of the strip or subsequent thereto, as desired, the edge of the hoop is rolled to form the bead 6, which projects outwardly of the hoop to form an annular channel or groove 9. If preferred, this bead and resultant channel may be formed

by rolling the metal after the ends thereof have been joined to form the hoop. The article then is in the form of a lengthened band having a bead at one end, and this band is then treated with suitable dies to press the lower portion thereof inwardly and upwardly to lie against the inner face of the band, and the extreme upper portion of this upwardly-bent part is then bent at the same operation to form an inwardly-directed flange or shelf, above referred to. There is thus produced a sheet-metal hoop having a channel at its upper portion and a shelf therebelow, so that the hoop may be disposed over the lower end of a can 11, so that the bottom of the can will rest upon the flange, while the outwardly-directed bead 12, adjacent to the bottom of the can, will engage in the channel 9 to hold the hoop onto the can, and by suitably placing the rivets that connect the ends of the hoop the channeled portion of the hoop may be sprung slightly outwardly, so that the bottom of the can may be forced into the hoop and the bead of the can engaged with the channel, the hoop returning to place to tightly impinge against the can to hold the hoop in place.

It will be understood that in practice any suitable material may be used for the hoop and any suitable proportions may be observed without departing from the spirit of the invention.

What is claimed is—

An article of manufacture, a bottom hoop for cans consisting of an endless band of sheet metal having one end bent inwardly and upwardly of the band to lie against the inner face thereof and then bent in the direction of the center of the band to form a supporting-shelf to receive a can, the upper portion of the band having an outwardly-directed bead and an inner resultant channel rolled or pressed therein to receive a bead on the can to which the hoop is to be attached.

In testimony that I claim the foregoing as my own I have hereto affixed my signature in the presence of two witnesses.

BERTINI T. WOOD.
